UNITED STATES PATENT OFFICE

JOHN L. LATTA, OF HICKORY, NORTH CAROLINA.

PUMP.

1,237,530.

Specification of Letters Patent. Patented Aug. 21, 1917.

Application filed September 25, 1916. Serial No. 122,107.

To all whom it may concern:

Be it known that I, JOHN L. LATTA, a citizen of the United States, residing at Hickory, in the county of Catawba and State of North Carolina, have invented a new and useful Pump, of which the following is a specification.

The present invention appertains to pneumatic displacement pumps, and is particularly an improvement over the pump disclosed in my co-pending application Serial No. 99,578, filed May 24, 1916.

It is the object of the invention to improve the pump whereby to facilitate the unseating of the valve controlling the exhaust or discharge of air, and a further object of the invention is to improve the means for controlling the flow of compressed air or pressure fluid into the cylinder or barrel for expelling the water or other liquid.

With the foregoing and other objects in view which will appear as the description proceeds, the invention resides in the combination and arrangement of parts and in the details of construction hereinafter described and claimed; it being understood that changes in the precise embodiment of the invention herein disclosed can be made within the scope of what is claimed without departing from the spirit of the invention.

The invention is illustrated in the accompanying drawing, wherein:

Figure 1 is a vertical section of the pump, portions being broken away.

Fig. 2 is a sectional detail of the head of the pump showing parts behind those shown in Fig. 1.

The present construction generally resembles that disclosed in the above mentioned application, and includes a vertical cylinder or barrel 1 providing a water chamber, and a cap 2 secured upon the upper end of the cylinder 1 and provided with an upstanding head 3. The lower end of the cylinder is closed by a cap 4 provided with a central upstanding pin or stud 5, and with water or liquid inlet apertures 6 surrounding the stud 5. A disk valve 7 is slidable upon the stud 5 to provide a check valve permitting of the inflow of liquid, but preventing the outflow of liquid through the apertures 6. The upward movement of the valve 7 is limited by a nut 8 or other stop carried by the stud 5. When the valve 7 gravitates onto the cap 4, it covers the apertures 6, to prevent the escape of water or

other liquid from the cylinder through said apertures.

The head 3 is provided with a vertical bore 9 providing a pressure fluid outlet, and said head has a counter bore or recess 10 at the lower end of the bore 9. A pressure fluid escape pipe or tube 11 has its lower end engaged with the head 3 to communicate with the bore 9, and can extend upwardly to any suitable point where it is desired to discharge the pressure fluid to the atmosphere. A depending tube 12 has its upper end engaged with the head 3 to communicate with the lower end of the bore 9, and projects downwardly centrally within the recess 10, the lower end of the tube 12 providing a valve seat 13. The pressure fluid, when the end of the tube 12 is uncovered, can pass to the atmosphere from the cylinder 1 by way of the tube 12, bore 9, and pipe 11.

A vertical tubular housing 14 has its upper end projecting loosely within the recess 10, around the tube 12, and a collar 15 is secured or fitted snugly within the upper end of the housing 14, and is slidable upon the tube 12. A coiled wire expansion spring 16 surrounds the tube 12 and has its upper end secured to the collar 15, said spring 16 being disposed within the housing 14 and being of such a length, that when the housing 14 is raised, the lower end of the spring 16 moves slightly above the valve seat 13.

Disposed loosely within the housing 14 is an upper resilient buoyant ball valve 17 seatable upwardly against the seat 13 to close the end of the tube 12, and the housing 14 is provided with air apertures 18 therein adjacent the end of the tube 12, or near the upper end of the housing. A second resilient buoyant ball valve 20 is disposed within the housing 14 below the valve 17, and said housing is provided with water apertures 21 therein adjacent its lower end. The valve 20 is seatable upon an annular valve seat 19 engaged within the lower end of the housing 14, and the housing is movable vertically or longitudinally of itself to control the discharge of pressure fluid from the cylinder.

The valve seat 19 depends from the housing 14 and is provided with leather cups 23 or other suitable packing thereon to provide a piston 22 working snugly in an upstanding cylinder 24, the lower end of which is attached to a horizontal coupling 25 dis-

posed within the cylinder 1 near the lower end thereof. The coupling 25 has a passage 26, one end of which communicates with the lower end of the cylinder 24, and the other 5 end of which communicates with the lower end of a tube or pipe 27 attached to the coupling 25. The upper end of the pipe 27 is attached to the head 3 to communicate with a water or liquid discharge passage 28 10 thereof, and a discharge or eduction pipe 29 for the water or other liquid is attached to the head 3 to communicate with the passage 28, and can extend to the point where it is desired to discharge the liquid when 15 elevated. The head 3 is provided with a cavity 31 for a check valve 30 to support the head or column of water in the pipe 29, and to prevent the downward or retrograde movement of the water. Any suitable check 20 valve can be used for this purpose.

The coupling 25 is provided with a depending boss 32 below the cylinder 24 and housing 14, and said boss is provided with an opening or aperture 33 extending there- 25 through and communicating with the lower end of the cylinder 24. A cup 34 has its open end threadedly or otherwise engaged upon the boss 32, and the coupling 25 is provided with a restricted passage or duct 30 35 having one end extending to the face of the boss 32 and communicating with the cup 34. A tube 36 of small diameter extends upwardly through the cap or bottom 4 of the cylinder 1 and has its upper end threadedly or otherwise engaged with the coupling 25 40 to communicate with the other end of the passage 35, a nut 37 or other retaining element being threadedly or otherwise engaged upon the lower terminal of the tube 36 and bearing against the cap 4 to assist in holding the parts assembled. The piston 22 has a depending spider 38 to which a depending stem 39 is connected, said stem projecting 45 loosely through the opening 33 and provided with a disk valve 40 of rubber or other suitable material seatable upwardly against the boss 32 to close the respective end of the passage 35 when the housing 14 is raised. The passage 35 and tube 36 provide an escape or relief conduit or passage establishing 50 communication between the well exteriorly of the pump and the lower end of the cylinder 24 when the valve 40 is unseated, as will hereinafter more fully appear.

The housing 14 is spring pressed or yield- 55 ably raised by spring tension and for this purpose, one or more coiled wire retractile springs 41 have their upper ends connected, as at 42, to the head cap 2, and have their lower 60 ends engaged with hooks 43 carried by the housing 14. The springs 41 serve to raise the housing when the pressure within the cylinder 1 is relieved.

The air or pressure fluid inlet means 65 includes a chamber or recess 44 provided in

the upper end of the head 3, and a passage 45 provided in said head and communicating at one end with the chamber 44 centrally of its bottom, the other end of the passage 45 communicating with the lower end of a pressure fluid supply pipe 46 attached to the head 3. A cap 47 is seated on the head 3, being secured thereto by means of bolts 48, or other securing elements, and a flexible diaphragm 49 is clamped between the cap 70 and head 3 to extend across the chamber 44. A passage 50 in the head 3 establishes communication between the chamber 44 and upper end of the cylinder 1, and a ball valve 51 is seatable on the bottom of the chamber 44 over the end of the passage 45, but there can be a slight leakage of air past the valve 51 when it is seated. A dished disk 52 is secured centrally to the under surface of the diaphragm 49 to bear upon the valve 51 and to hold it in place adjacent to the passage 45, and a bearing disk 53 is preferably secured upon the upper surface of the dia- 80 phragm to receive the pressure of a coiled wire expansion spring 54 confined between the disk 53 and top of the cap 47. The spring 54 is of the proper tension to depress the diaphragm 49 whereby to seat the valve 51 when the pressure in the cylinder 1 is relieved.

In operation, the cylinder 1 is submerged 85 in water or other liquid which is to be elevated, and when the pressure within the cylinder is relieved, the water will flow by gravity through the apertures 6 into the cylinder, the check valve 7 seating over said apertures to prevent the escape of water there- 90 through. Before the cylinder 1 is filled with water, the valves 20-17 gravitate within the housing 14, and as the cylinder becomes filled with water, the water will fill the housing 14, and will float the valves and carry them upwardly until the valve 17 is seated against the lower end of the tube 12, thereby preventing the further escape of air 95 from the cylinder by way of the tube 12, bore 9 and pipe 11 which communicate with the atmosphere. During the time that the valve 17 is unseated, the pressure within the cylinder 1 is relieved, being exhausted to the atmosphere, and this will relieve the pressure in the chamber 44, so that the spring 54 depresses the diaphragm 49 and holds the valve 51 seated. There is, however, a slight leakage of pressure fluid past the valve 51 100 so that the air flows from the chamber 44 through the passage 50 into the cylinder 1 and thence to the atmosphere by way of the tube 12. This leakage of pressure fluid or air is only slight, so as to eliminate waste. 105 Now, assume that the cylinder 1 is filled with water, with the valve 17 seated against the tube 12, to prevent the escape of pressure fluid, the housing 14 being 110

raised, to retract the spring 16 so that the valve 17 can seat without interference. The valve 40 is also seated to close the passage 35. The valve 20 is below the valve 17. 5 When the valve 17 is seated against the tube 12, this prevents the escape of pressure fluid to the atmosphere, and the pressure within the chamber 44 will immediately accumulate and increase to such an extent that the dia- 10 phragm 49 is raised against the tension of the spring 54, thus permitting the valve 51 to be forced from its seat by the pressure fluid, whereby the pressure fluid can now flow uninterruptedly into the cylinder by 15 way of the chamber 44 and passage 50. The pressure fluid will force the water downwardly within the cylinder through the apertures 21 of the housing 14 into the lower end of said housing, and thence through the 20 valve seat 19 into the cylinder 24. From the cylinder 24, the water is forced through the passage 26, pipe 27, passage 28, and pipe 29 to the point of discharge, the water being displaced by the pressure fluid, and being 25 elevated thereby. The valve 17 is held seated by the pressure, during the meantime. When the water is discharged to the level of the apertures 21, the discharge of water from the cylinder or tank 1 is arrested. 30 During the time that the water is being ejected from the cylinder, the valve 20 will move downwardly with the level of the water in the housing 14, so that when the water level reaches the seat 19, the valve 20 35 will seat thereon, thereby preventing the further escape of water or the escape of pressure fluid through the water outlet conduit. Consequently, the pressure in the cylinder will force the piston 22 down- 40 wardly with the housing 14 in the cylinder 24, and the housing 14 being moved downwardly, will move the upper end of the expansion spring 16 downwardly, thereby bringing said spring 16 under compression 45 upon the valve 17. The spring 16 when thus compressed tends to force the valve 17 from its seat. Furthermore, when the housing 14 is moved downwardly, the stem 39 being moved downwardly by the housing, 50 will unseat the valve 40, thereby bringing the relief passage 35 into communication with the lower end of the cylinder 24. The water within the cylinder 24 below the piston 22 can therefore be readily expelled 55 from the pump by way of the opening 33, cup 34, passage 35 and tube 36. This will immediately relieve the pressure below the piston 22, whereby the pressure within the cylinder 1 will force the piston 22 and hous- 60 ing 14 downwardly by a quick motion, thereby bringing the spring 16 under quick compression. The spring 16, instead of being compressed gradually, is thus brought under quick compression, and the tension is 65 sufficient to force the valve 17 downwardly

from its seat by a quick or sharp movement, thus throwing the valve 17 beyond the range of the rush of pressure fluid from the cylinder through the tube 12. This prevents the rush of pressure fluid to the atmosphere by way of the tube 12 from sucking the valve 17 back against its seat, since the action of the spring 16 as above described will completely throw the valve 17 out of the range of the air suction. The 70 action of the spring 16 is greatly enhanced by the downward movement of the housing 14 caused by the relief of the water pressure below the piston 22 in the cylinder 24. The valve 17 being unseated at once relieves the 75 pressure in the cylinder, since the pressure fluid can now flow to the atmosphere by way of the tube 12, passage 9 and pipe 11. At the moment that the valve 17 is thrown from its seat, so that there is a reduction in 80 pressure in the cylinder, this reduction also extends into the secondary chamber 44, to lessen the upward pressure against the dia- 85 phragm so that spring 54 seats valve 51. There is a slight leakage of pressure fluid 90 past the valve 51, when it is seated as above stated. There is only a slight flow of pressure fluid when the cylinder is being re- 95 filled. This prevents a wastage of air, and also facilitates the operation of the pump, 100 since the water can flow into the cylinder 1 by way of the apertures 6 quickly to again fill said cylinder for a new operation. As soon as the valve 17 has been unseated and the pressure relieved, the housing 14 is 105 again raised under the influence of its springs 41, whereby to seat the valve 40. Then when the valve 17 is brought against its seat 13, to shut off the flow of pressure 110 fluid or air to the atmosphere, the cylinder 1 having been filled with water, the pressure 105 is again brought to bear in the cylinder 1 as above indicated. The operation is repeated the same as before, and the operation re- 115 peated intermittently as long as the pressure 120 fluid is turned on.

Attention is directed to the fact that the valve 51 is operated by the variations in pressure, whereby when the pressure within the cylinder 1 is relieved, the valve 51 is op- 115 erated to reduce the flow of air to the cylin- 120 der, whereas when the valve 17 is seated to again cause the accumulation of pressure, the valve 51 is returned to normal position to again establish full communication be- 125 tween the pressure fluid supply passage and cylinder 1.

Having thus described the invention, what is claimed as new is:

1. A pump embodying a chamber having 125 a liquid inlet, a pressure fluid inlet, a pres- 130 sure fluid outlet and a liquid outlet, the li- 135 quid outlet including a cylinder, a piston for the cylinder, a valve seatable against the piston for closing the liquid outlet when the

liquid level is lowered a predetermined amount, a valve for the pressure fluid outlet, spring means for throwing the pressure fluid outlet valve open when said piston 5 is moved by pressure within said chamber, and a passage communicating with said cylinder and the atmosphere, and a valve for closing said passage and operated by the piston to move open when the piston starts 10 to move to instantly relieve pressure in the cylinder.

2. A pump embodying a chamber having a liquid inlet and outlet and a pressure fluid inlet and outlet, the liquid outlet including 15 a cylinder, a piston working in said cylinder, a valve coöperable with said piston for closing the liquid outlet when the liquid level lowers a predetermined amount in said chamber, a valve for closing the pressure 20 fluid outlet, means operated by the piston for unseating the second mentioned valve when the piston is moved by pressure fluid in said chamber, a relief passage having one end extending away from and communicating 25 with said cylinder and its other end leading to the exterior of the pump, and a valve for normally closing the first-mentioned end of said relief passage and moved to open position away from said passage when said 30 piston is moved.

3. A pump embodying a chamber having a liquid inlet, a pressure fluid inlet and outlet, a member having a liquid outlet and a cylinder communicating therewith, a piston working in said cylinder, a valve coöperable 35 with said piston to close the liquid outlet when the liquid level lowers a predetermined amount, a valve for closing the pressure fluid outlet, means for unseating the second 40 mentioned valve when the piston is moved, said member having a relief passage having one end extending away from and communicating with the cylinder and its other end leading to the exterior of the pump, and 45 a valve connected to the piston for normally closing the first-mentioned end of said passage and moved to open position when said piston is moved by the pressure fluid in the chamber.

4. A pump embodying a chamber having a liquid inlet, a pressure fluid inlet and outlet, a member having a liquid outlet and a cylinder communicating therewith, a piston working in said cylinder, a valve coöperable 50 with said piston to close the liquid outlet when the liquid level lowers a predetermined amount, a valve for closing the pressure fluid outlet, means for unseating the second mentioned valve when the piston 55 is moved, said member having a boss, an opening extending through said boss, and a relief passage extending to the face of the boss and communicating with the exterior 60 of the pump, a cup engaged upon said boss, 65 a stem connected to the piston and project-

ing through said opening, and a valve carried by said stem seatable against said boss to close said opening and passage.

5. A pump embodying a chamber having a liquid inlet and outlet and a pressure fluid 70 inlet and outlet, means for stopping the outlet of pressure fluid and liquid, a valve controlling the inlet of pressure fluid and allowing leakage when closed, and means communicating with said chamber and pressure 75 fluid inlet for causing the valve to move to open position upon the accumulation of pressure in said chamber and to move to closed position when the pressure in said chamber is relieved. 80

6. A pump having a chamber, a liquid inlet and outlet for said chamber, and a pressure fluid outlet and pressure fluid supply means for said chamber, means for stopping the outlet of the pressure fluid and liquid, a 85 valve for shutting off the flow of pressure fluid into said chamber and allowing leakage when closed, and means tending to close said valve upon the reduction of pressure and adapted to be moved upon the accumulation 90 of pressure to permit said valve to open.

7. A pump having a chamber, a liquid inlet and outlet for said chamber, and a pressure fluid inlet and outlet for said chamber, 95 means for stopping the outlet of pressure fluid and liquid, a valve seatable toward the pressure fluid inlet for shutting off the flow of pressure fluid into said chamber and allowing leakage when closed, and spring 100 means tending to seat said valve and operated by the accumulation of pressure in said chamber to release the valve.

8. A pump having a chamber, a liquid inlet and outlet for said chamber, and a pressure fluid inlet and outlet for said chamber, means for stopping the outlet of pressure fluid and liquid, and means for reducing but not stopping the flow of pressure fluid into said chamber from the inlet including a 110 diaphragm to bring said means into operation upon a reduction of pressure in said chamber and to bring said means out of operation upon the accumulation of pressure in said chamber. 115

9. A pump having a chamber, a liquid inlet and outlet for said chamber, and a pressure fluid inlet and outlet for said chamber, means for stopping the outlet of pressure fluid and liquid, a valve for reducing the 120 flow of pressure fluid from the inlet into said chamber and allowing leakage when closed, and a diaphragm subjected to the pressure in said chamber for moving said valve to closed position upon the reduction 125 of pressure in said chamber and to permit said valve to open upon the accumulation of pressure in said chamber.

10. A pump having a liquid chamber, a secondary chamber communicating there- 130

with, a liquid inlet and outlet for the liquid chamber, a pressure fluid outlet for the liquid chamber, and a pressure fluid inlet communicating with the secondary chamber, 5 means for stopping the outlet of liquid and pressure fluid, a valve within the secondary chamber to reduce the flow of pressure fluid into said chamber and allowing leakage when closed, and means within the secondary chamber for moving said valve to closed 10 position upon the reduction of pressure therein.

11. A pump having a liquid chamber, a secondary chamber communicating therewith, a liquid inlet and outlet for the liquid chamber, a pressure fluid outlet for the liquid chamber, and a pressure fluid inlet communicating with the secondary chamber, means for stopping the outlet of liquid and pressure fluid, a valve within the secondary chamber to reduce the flow of pressure fluid into said chamber and allowing leakage when closed, and a diaphragm extending across the secondary chamber to 20 move said valve toward closed position upon the reduction of pressure in said chamber.

12. A pump having a liquid chamber, a secondary chamber, a liquid inlet and outlet for the liquid chamber, a pressure fluid outlet for the liquid chamber, and a pressure fluid inlet 34 communicating with the secondary chamber, said secondary chamber communicating with the liquid chamber, a diaphragm extending across the secondary chamber, a cap clamping said diaphragm in place, spring means between the cap and diaphragm to move the diaphragm toward the pressure fluid inlet, a valve within the secondary chamber moved by the diaphragm toward the pressure fluid inlet to reduce the 40 flow of pressure fluid and allowing leakage when closed, and means for stopping the outlet of pressure fluid and liquid from the liquid chamber.

In testimony that I claim the foregoing 45 as my own, I have hereto affixed my signature in the presence of two witnesses.

JOHN L. LATTA.
